TRESTLE

John L. Pozun and Le Roy Houghton, Johnstown, Pa., assignors of one-third to Howard C. Faust, Johnstown, Pa.

Application March 3, 1947, Serial No. 732,004

1 Claim. (Cl. 304—5)

1

Our invention relates to improvements in trestles for use in erecting scaffolding such as is used by painters, paper hangers, carpenters, and the like.

The primary object of our invention is to provide a simply constructed trestle of the extensible ladder type for holding scaffold boards, at selected heights, and which is especially adapted for positioning close to a building wall, but is stabilized in the construction thereof against tilting away from the wall, when so placed, and is formed of tubing and angle and channel iron, basically, in a manner to render the same strong and safe, yet easy to handle, and comparatively inexpensive to manufacture.

Other and subordinate objects, also comprehended by our invention, together with the precise nature of our improvements and the advantages thereof will be readily understood when the succeeding description and claims are read with reference to the drawings accompanying and forming part of this specification.

In said drawings:

Figure 1 is a view in side elevation, with parts in section, of our improved trestle in a preferred embodiment thereof.

Figure 2 is a view in rear elevation.

Figure 3 is a view in plan, with parts shown in section.

Figure 4 is a view in horizontal section taken on the line 4—4 of Figure 1.

Figure 5 is a view in vertical section taken on the line 5—5 of Figure 1.

Referring to the drawings by numeral, our improved trestle, as shown, comprises a base structure including a pair of opposed A-shaped, upright side frames 1, 2 diverging downwardly, relatively, and each embodying a straight top cross-bar 3 and a pair of legs 4, 5, in each frame, diverging downwardly relatively, from the ends of the top cross-bars 3. The legs 4 constitute rear legs and the legs 5 front legs, for reasons presently apparent. At a suitable distance from the lower ends of the legs 4, 5 for stepping thereon from the ground, a side cross round 6 connects the legs 4, 5 of each frame 1, 2, a similar, rear cross round 7 connects the rear legs 4, and another similar, front cross round 8 connects the front legs 5. Another front cross round 9 connects the front legs 5 substantially midway between the front round 8 and the top cross-bars 3. A pair of top angle bars 10 extending crosswise over the top corners of the side frames 1, 2, and which are fitted over said corners and welded thereto, as at 11, connect said side frames 1, 2 together at the

2

tops thereof with the top cross-bars 3 spaced apart a distance suitable for a purpose presently apparent. The side frames 1, 2 are formed of metal tubing welded at the upper corners of said frames, as at 12, the cross rounds 6, 7, 8, 9 being similarly formed and welded in place, as at 13, and the top angle bars 10 being formed of similar metal.

A particular feature of our invention is that the rear legs 4 incline downwardly and rearwardly at a slight angle to the vertical so that said rear legs may be placed close to a building wall, represented at 14, close to a perpendicular position, whereas, the front legs 5 are inclined at a greater angle to the vertical downwardly and forwardly, which, together with the angle of divergence of the legs 4, 5 in each frame 1, 2 serves to stabilize the described base structure against tilting away from the wall 14, or sidewise.

The base structure described in the foregoing is designed to support an upright extension section in the form of a ladder 15 having tubular sides 16 and similar cross rounds 17 welded to the sides, as at 18, and all formed of metal. The sides 16 are slidably fitted, for vertical adjustment of the ladder 15, between the top cross bars 3 and the top angle bars 10.

A channel bar 19 extends between the rear and front cross rounds 7, 8 in the transverse center thereof, and serves as a rest for the lower ends of the sides 16 when the ladder 15 is fully lowered. The channel bar 19 is welded, as at 20, to said cross rounds 7, 8.

A pair of upright angle bars 21 arising from the channel bar 19 with lower ends welded to said bar 19, as at 22, and upper ends, welded, as at 23, to the top angle bars 10, serve as guides for the sides 16 of the ladder 15 in adjusting said ladder.

For supporting the ladder 15 in different adjusted positions, above the channel bar 19, a trough shaped keeper bar 24 is hinged to one top cross-bar 3 to be swung into bridging relation to said top bars 3 under a selected round 17 of the ladder 15. The hinge for the keeper bar 24 comprises an edge hinge barrel 25 thereon, through which a pintle rod 26 extends with the ends thereof working in a pair of hinge barrels 27, welded, as at 28, to one top cross-bar 3 and between which the hinge 25 is fitted. As will be clear, when the keeper bar 24 is swung into bridging relation to said top cross-bars 3, the free side edge thereof rests upon the top cross-bar 3 opposite the one upon which said keeper bar 24 is hinged.

As will now be manifest, the ladder 15 is de-

signed to support on the rounds 17 thereof the usual scaffold boards, as represented at 29 in Figure 1. When it is desired to adjust the ladder 15, when held by the keeper bar 24, it is merely necessary to lift said ladder sufficiently to elevate a round off said keeper bar 24 so that said keeper bar may be swung out from under said round. The ladder 15 may then be adjusted, as occasion may require, and the keeper bar 24 swung under the appropriate round 17, after which said ladder may be lowered to seat the round in said bar. The front cross rounds 8, 9 and the angle bar 10 at the front of the base structure provide a ladder section for mounting to the ladder 15. The rounds 6, 7 are solely brace members.

The foregoing will, it is believed, suffice to impart a clear understanding of our invention without further explanation.

Manifestly, modifications of the invention, as described, may be resorted to without departing from the inventive concept, and right is herein reserved to such modifications as fall within the scope of the appended claim.

What we claim is:

In a trestle of the class described, a pair of opposed base frames diverging downwardly relatively, and each including a top bar and a pair of legs diverging downwardly from the top bar, a pair of cross bars connecting said frames to-

gether at the top corners thereof in spaced apart relation, cross rounds connecting the legs of the opposed frames adjacent the bottoms thereof, a horizontal bar extending between said cross rounds, a pair of angle bars upstanding from said horizontal bar with channel sides facing, a ladder section with rungs and slidably fitted in said angle bars to be slid into a position of rest on said horizontal bar and to be vertically adjusted off said horizontal bar, said ladder section slidably fitting between the pair of cross bars, and a trough-like keeper bar swingable on one top bar under rungs of said ladder section into bridging relation to said top bars to hold said section in adjusted position off said horizontal bar.

JOHN L. POZUN.
LE ROY HOUGHTON.
